S. W. LUITWIELER.

PUMP PISTON.

APPLICATION FILED FEB. 28, 1913.

1,214,696.

Patented Feb. 6, 1917.

UNITED STATES PATENT OFFICE.

SAMUEL W. LUITWIELER, OF ROCHESTER, NEW YORK.

PUMP-PISTON.

1,214,696.

Specification of Letters Patent. Patented Feb. 6, 1917.

Application filed February 28, 1913. Serial No. 751,250.

To all whom it may concern:

Be it known that I, SAMUEL W. LUITWIELER, of Rochester, in the county of Monroe and State of New York, have invented 5 certain new and useful Improvements in Pump-Pistons; and I do hereby declare the following to be a full, clear, and exact description of the same, reference being had to the accompanying drawings, forming a 10 part of this specification, and to the reference-numerals marked thereon.

My invention relates to improvements in pump pistons of the reciprocating type, characterized generally by a valve which 15 opens on the down stroke of the piston to permit the passage of water upwardly and closes on the up stroke to raise and force out the water, and it has for its object to provide a piston or plunger of novel construction, having for a chief advantage its 20 lightness in weight, and a comparatively low cost of manufacture.

Another object of my invention consists in the provision of an arrangement whereby 25 the flexible packing rings can be readily applied and fixedly secured in such a manner as to insure their being properly positioned on the piston frame, thus adding materially to the efficiency of the operation of the 30 piston.

A further object of my invention consists in the means whereby I make it possible to simultaneously apply or remove a series of 35 packing rings and to hold them all in position by a single securing means.

To these and other ends the invention consists in certain improvements and combinations of parts all as will be hereinafter more fully described, the novel features being pointed out in the claim at the end 40 of the specification.

In the drawings: Figure 1 is a vertical section view of a piston embodying a preferred application of my improvement; Fig. 45 2 is a sectional view on the line 2^a—2^a of Fig. 1, and Fig. 3 is a bottom plan view.

Similar reference characters throughout the several figures indicate the same parts.

In the embodiment of the invention as 50 herein described and illustrated, 1 designates a piston rod which is attached at its lower end to a threaded sleeve 2, which is in turn secured on the upper end of the piston frame. Said piston frame comprises 55 a hub portion 3 on which are formed a plurality of radially projecting walls or webs

4 which extend a substantial distance below the bottom of the hub portion, the lower ends of the walls 4 being reduced, and connected by the annular ring 5 which is provided with integrally formed enlarged portions 6 having threaded openings 7 therein for a purpose presently to be mentioned. The walls 4 are connected at their upper ends by the annular portion 8 having a recess therein constituting the beveled valve seat 9 tapering inwardly and downwardly and adapted to receive the valve 10, which is arranged on the beveled hub 3, tapered in an opposite direction to the seat 9 to 70 form a second valve seat for the lower portion of the valve, said valve being movable vertically between the valve seats and the lower end of the sleeve 2. The annular portion 8 is extended downwardly for some distance and is provided at its lower end with the reduced portion or flange 11 affording a supporting surface for the uppermost 75 packing ring 12. The annular portion 8 is undercut at 13 for the purpose of more 80 rigidly retaining the packing ring in position, as will be more clearly shown herein-after.

14 designates an annular ring formed integral with the walls 4 and connecting the latter to afford a seat for the packing ring 15 while the lowermost packing ring 16 engages the aforementioned annular ring 5.

17 designate spacing rings arranged between the respective packing rings, the engaging edges of the rings 17 being beveled or inclined as shown, so as to afford a substantially dovetailed recess for holding the packing rings in position. The packing rings and spacing rings are arranged loosely on 95 the piston frame, being held in position by a suitable means which serves to retain all the parts in their proper assembled relation.

To this end, I provide a securing ring 18 open at its center having a beveled edge 19 arranged to engage the lowermost packing ring 16 and provided with a series of inwardly extending lugs having openings through which pass the bolts 20 having engagement with the threaded openings 7 in the frame. The securing ring 18 is held by means of nuts 21 which engage the bolts 20, the latter being slotted at 22 to receive wires 23, which are passed over the lugs 24 as shown, and serve as effective means for locking the several nuts against turning movement.

By this construction, an extremely simple device is afforded, the arrangement being such that every part of the metal is utilized, and all unnecessary parts are omitted, thus 5 reducing the weight of the piston to a minimum without affecting its strength and durability.

With my present construction it is a comparatively simple matter to assemble the 10 several packing rings and they are secured by a rigid fastening means, being gripped by an even pressure throughout, without having any twisting or side strains imparted to them, as the pressure of the fastening 15 means comes only in a direction transversely of the walls of the packing rings. The piston can be quickly dismantled, and when the rings are in place, they cannot by any possibility become accidentally loosened.

20 I claim as my invention:

A pump piston comprising a frame embodying a hub and a plurality of radially extending ribs formed on the hub, the ribs being connected at their upper ends by an

annular surface and extending at their lower 25 ends below the hub, enlargements carried by the lower ends of the ribs, packing rings loosely mounted upon the ribs, the uppermost of which is adapted to engage said annular surface, spacing rings also loosely 30 mounted upon the ribs and disposed between the packing rings, a securing ring a portion of the inner face of which is mounted in sliding engagement with the ribs and adapted 35 to retain the lowermost packing ring, said securing ring being open at its center and mounted independently of the hub, enlargements projecting inwardly from the securing ring and terminating substantially beneath the first mentioned enlargements and 40 means carried by the second mentioned enlargements in engagement with the first for supporting said securing ring.

SAMUEL W. LUITWIELER.
